Filed Mar. 23, 1970, Ser. No. 22,005

Term of patent 14 years

Int. Cl. D23—04

U.S. Cl. D23—140

FIG. 1

FIG. 2

FIG. 3

FIG. 4

FIG. 1 is a three-quarter perspective view of a combined lighting and ventilating fixture showing our new design;

FIG. 2 is a top plan view thereof;

FIG. 3 is a side elevational view thereof; and,

FIG. 4 is a bottom plan view thereof.

The cross hatching on the bottom of the fixture indicates conventional lens faceting and is understood to be continuous over the area on which it is shown.

We claim:

The ornamental design for a combined lighting and ventilating fixture, substantially as shown and described.
